BY

Carl A. Crawford
ATTORNEY

UNITED STATES PATENT OFFICE.

CARL W. ART, OF SPOKANE, WASHINGTON.

CALCULATOR.

Application filed November 26, 1924. Serial No. 752,487.

To all whom it may concern:

Be it known that I, CARL W. ART, a citizen of the United States, residing at Spokane, in the county of Spokane and State 5 of Washington, have invented new and useful Improvements in Calculators, of which the following is a specification.

This invention relates to improvements in calculators.

10 One of the features of this invention is to embody a calculator in a novel form wherein the result sought, will be invisible from that side or face toward which the user views the device when making the initial adjustment, and wherein the result will only be visible after the adjusted calculator has been reversed in position from its initial 15 position. Thus I embody in my improved device an element of surprise which is or 20 may be capitalized by associating with it the idea of "fortune telling." This phase of the invention is advantageously emphasized by embodying the adjustable elements or members of the calculator either in the 25 form of, or in attractive simulation of the usual playing cards.

While my invention is not limited to the specific form shown, still, it is a feature to equip the members of the calculator with interdependent indicia whereby said members 30 may first be adjusted to denote the age of the user, and then further adjusted to denote the periodic savings. By then reversing the calculator, as thus far adjusted, the 35 user will see totalized, the amount his savings would aggregate when he has reached a fixed advanced age. In other words, calculation is made of periodic savings or payments for a term of years, irrespective of 40 whether the savings or payments are directed to a bank account, an insurance policy, or analogous scheme.

Other features and objects of my invention will be more fully described in connection 45 with the accompanying drawings and will be more particularly pointed out in and by the appended claims.

In the drawings:

Fig. 1, is a view in side elevation of my 50 improved calculator embodied in card form with the cards disposed in abutting registry.

Fig. 2, is a view of the side reverse from that shown in Fig. 1.

Fig. 3, is a view of the device looking at 55 the obverse faces thereof and showing the

initial adjustment of the selector card to a position denoting the age of the user.

Fig. 4, is a view showing the second adjustment wherein the intermediate indicating card and the periodic card have been 60 adjusted to indicate the periodic savings each month.

Fig. 5, is a view of the cards in the same adjustment shown in Fig. 3, but reversed in position so that the user is now looking at 65 the reverse faces whereon is indicated the sum the user would have if he saved the amounts each month shown on the obverse faces in Fig. 4.

Like characters of reference designate similar parts throughout the different figures of the drawings.

I will now describe the specific form of my invention herein shown. First identifying the physical elements, a selector card is 70 employed having an obverse face 1 and a reverse face 2, this card being one of the outer cards. An intermediate indicating card has an obverse face 3 and a reverse face 4. A periodic card has an obverse face 80 5 and a reverse face 6, and this card is also one of the outer cards. These three cards are movably united to be relatively adjusted out of lateral abutting registry, as shown in Figs. 1 and 2, into selective positions 85 shown in Figs. 3 to 5, for instance. I preferably unite these cards by a pivotal connection as indicated at 7, and as shown, this connection 7 is located adjacent one corner of the cards and the arrangement is such 90 that the cards open, when adjusted, in a good deal the fashion of a hand of playing cards. In practice, I find it an advantageous feature to employ cards of substantially the size and shape of playing cards and the free portions of the faces of said cards may 95 advisedly be ornamented to simulate playing cards, thereby carrying out the "fortune telling feature." However, my invention is not limited to the inclusion of these features and its utility as a calculator makes it 100 capable or susceptible of a widely different range of physical embodiment.

Disposed and operable from the obverse face of the selector card is an opening 8 for disclosure therethrough of certain age indicative numbers. The selector card also has a registering edge 9, which is intersected by an index device preferably in the form of an arrow 10.

The indicating card has on its obverse face a series of age indicative numbers 11, affording a range from 26 to 35. This of course is a very narrow range and has been shown thus limited in order to illustrate the numbers in large size for proper reproduction on a reduced scale. However, in practice, a much greater range of age will be provided. These age numbers, as will be seen from Fig. 4, are disposed in concentric relation to the pivotal connection 7, so that as the selector card is adjusted, the opening 8, will consecutively disclose said age numbers. On the same face 3, of the indicating card is a series of connecting or continuity lines 12, which are preferably provided with enlarged terminals 13, for selective registry with arrow 10, next to edge 9, of the selector card. These lines 12, at their opposite ends, terminate at edge 15, of the indicating card. It will be noted that there is one connecting line for each age number.

On face 5, of the periodic card, are disposed a series of periodic or monthly savings numbers. These numbers are shown arranged in columnar form, the columnar lines 16 converging in a manner to laterally register with edge 15, as the indicating card is adjusted to various positions. These columnar lines are transversely intersected by lines 17, which are concentrically disposed with respect to pivot 7.

I will next refer to the reverse faces of the cards. The reverse face 6, of the periodic card may appropriately form the title face on which any suitable name of a bank or insurance company and its building may be disposed, together with the title given to the calculator.

The reverse face 4, of the indicating card has a series of converging division lines 18, adapted for registry with edge 19, of the periodic card. Aggregate or total amount sums 20, are disposed between the division lines 18.

On the reverse face 2, of the selector card is disposed an informative legend 21, with arrows 22, directing notice of the user to the largest sum adjacent edge 19.

I will next describe the manner in which the calculator is operated, and to facilitate such description, I will hereinafter designate the selector card by A, the indicating card by B and the periodic card by C.

The user will dispose the cards as shown in Fig. 2, viewing face 1, of the selector card A. He will next shift card A, to the left of the other cards, as shown in Fig. 3, until the opening 8 discloses an age number nearest the age of the user. Assuming that the age is thirty, as shown, the index 10, will register with connecting line a. Now the user must next determine how much he can save each month, therefore, he will retain the adjustment of the cards A and B,

already made, and move card C, to the right of card B, until edge 15, and line a, registers with the amount which the user can save each month, which as shown, is \$21.96. Now if he can save \$21.96 each month until he reaches a certain advanced age, he will want to know, at a given interest rate, what he will have accumulated. Therefore, with the cards still in the adjustment shown in Fig. 4, he will turn them around to view the reverse faces as shown in Fig. 5. He will then see that at the age of sixty-five years, he will have accumulated \$20,000, and that will be his fortune, as told by this adjustment.

It will be noted that while the user is adjusting the cards and viewing the obverse faces thereof, he is observing the searching or finding indicia, whereas when he wants to find out what his fortune is, and reverses the cards, he will be viewing the answering indicia.

It will now be clear that there is a plurality of adjustments necessary before the fortune can be told, first; the age or primary adjustment of cards A and B, relatively to each other, and second; the determining or secondary adjustment of card C, relatively to card B.

The arrows 22, have a plurality of arrow heads properly spaced apart so that one will always be adjacent edge 15, and directing attention to the highest amount immediately adjacent said edge.

The device of my invention is primarily designed as an attractive and interesting arresting token to be given out free by savings and loan institutions, banks, insurance companies and other concerns desirous of attracting the public's attention to the advantages of regular savings. It will therefore be seen that while I have shown the device apparently designed for a bank, that it could easily be modified as regards arrangement of the figures and legends to serve an insurance company, without departing from the spirit of my invention.

It is believed that the device of my invention will be fully understood from the foregoing, and while I have herein shown one specific embodiment thereof, I do not wish to be limited thereto, except for such limitations as the claims may import.

I claim:—

1. A calculator comprising an outer selector card, an intermediate indicating card, an outer periodic card, said cards being movably united for selective adjustment of the cards with respect to each other, said selector card having an age number disclosing opening and a periodic index device on its obverse face, said indicating card having a series of age indicative numbers arranged for disclosive registry through said opening and also a series of continuity lines on

its obverse face for registry with said index device, said periodic card having on its obverse face a series of columnar arranged periodic numbers adapted for registry with said continuity lines in transverse relation to the columnar division of said numbers, whereby the selected age may be brought into selected registry with a series of periodic numbers, and the reverse face of 10 said indicating card having totalizing amounts for registry with the reverse side of said periodic card thereby totaling the aggregate amount of the selected transverse periodic numbers on the obverse face 15 of said periodic card.

2. A calculator comprising an outer selector card, an intermediate indicating card, an outer periodic card, said cards being pivotally connected adjacent one lower corner of the cards for selective adjustment of 20 said cards out of lateral abutting registry, said selector card having an age number disclosing opening and a periodic index device on its obverse face, said indicating card 25 having on its obverse face a series of age

indicative numbers disposed concentrically with respect to said pivotal connection for disclosive registry through said opening, and the obverse face of said indicating card also having a series of curved continuity lines 30 provided with terminals arranged concentrically with respect to said pivotal connection and adapted for selective registry with said index device and the remaining ends of said lines terminating at the most adjacent edge of said card, said periodic card having on its obverse face a series of convergingly columnar arranged periodic savings numbers transversely divided by lines 35 disposed concentrically to said pivotal connection and adapted for selective registry with the card edge ends of said continuity lines, and the reverse face of said indicating card having totalizing amounts arranged 40 for indicative registry with one edge of said 45 periodic card, substantially as and for the purposes described.

In testimony that I claim the foregoing as my own, I hereby affix my signature.

CARL W. ART.
